UNITED STATES PATENT OFFICE.

ROBERT H. OWEN, OF BUTTE, MONTANA, ASSIGNOR OF ONE-THIRD TO EDWARD F. MAGINN AND ONE-SIXTH TO M. H. GLEASON, BOTH OF BUTTE, MONTANA.

CYLINDER FOR THRASHING MACHINES.

1,424,933.

Specification of Letters Patent. Patented Aug. 8, 1922.

Application filed November 2, 1921. Serial No. 512,252.

To all whom it may concern:

Be it known that I, ROBERT H. OWEN, a citizen of the United States, and a resident of Butte, in the county of Silver Bow and State of Montana, have invented certain new and useful Improvements in Cylinders for Thrashing Machines, of which the following is a specification.

My present invention relates generally to thrashing machines and more particularly to the cylinders thereof, my object being the promotion of a cylinder of a simple economical structure in which provision is made for the ready renewal of broken or otherwise unserviceable teeth and a further object is to enable the teeth to be replaced easily and quickly without the necessity of long complicated wrenches, as well as an arrangement in which the teeth will be rigidly held in their connected position against shifting movement or displacement.

In the accompanying drawings which illustrate my present invention and form a part of this specification,

25 Figure 1 is a top plan view of a cylinder for thrashing machines constructed in accordance with my invention,

Figure 2 is an end view thereof,

30 Figure 3 is a face view, looking from the inside, of one of the end plates,

Figure 4 is a top plan view thereof,

Figure 5 is a partial transverse section taken adjacent to the central partition or supporting plate,

35 Figure 6 is a cross section through one of the tooth bars adjacent to one of the tooth seats thereof,

Figure 7 is a side view of the parts shown in Figure 6,

40 Figure 8 is a detail perspective view of a portion of one of the end plates looking from the inside thereof,

Figure 9 is a detail section taken on line 9—9 of Figure 7, and

45 Figure 10 is a partial longitudinal section taken on line 10—10 of Figure 1.

Referring now to these figures and particularly to Figure 1 I have shown a shaft at 10 on which the cylinder proposed by my invention is secured, the opposing end plates 11 of the cylinder having central hubs 12 provided with key slots 13 adjacent to their shaft receiving bores for the above purpose.

50 In addition to the two end plates 11 the cylinder includes a central or partition plate 14 which, like the end plates 11, have periph-

eral slots, the side walls 15 of which slots are provided with inner obliquely undercut sections 16 conformable to the shape of the tooth bars 17 whose end portions extend into 60 the peripheral slots or grooves of the end plates 11 and whose central portion extends through the conformably shaped peripheral slots or grooves of the partition plate 14.

It will be noted from Figures 2, 5, 6 and 7 65 that the tooth bars 17 have the outer portions of their side walls parallel and have their inner portions flared so that they thus slidably interfit the openings peripherally of the end plates 11 and partition plate 14, each of 70 the bars 17 having secured to its inner face anchor plates 18, the connection of which is effected by machine screws 19 threaded into the bars and whose positioning in endwise abutting relation against the inner surfaces 75 of the end plates 11 thus holds the bars against lengthwise displacement under normal circumstances. Upon removal of one of the anchor plates the tooth bars may be shifted in the direction of their length out 80 of the cylinder.

Each tooth bar 17 is also provided in its length with transversely disposed and tapering recesses 20 into which the inner reduced portions 21 of the transversely 85 tapering teeth 22 are adapted to interfit, each tooth having a transverse opening adjacent to its inner end to aline with an opening 23 transversely of the tooth bar in communication with its recess 20, for the reception of 90 a connecting bolt 24. By reducing the inner end of each tooth 22, the latter is left with an inwardly facing shoulder 25 as clearly shown in Figure 6 abutting the outer face of the tooth bar which, in conjunction with the taper of the tooth in both lengthwise and transverse directions and similar tapers of the walls of the tooth bar slots or recesses, 95 obviously forms a strong supporting connection for the tooth by virtue of which 100 breakage is to a great extent avoided.

Should a tooth break it is quite obvious that it is simply necessary to remove the nut 26 of the bolt 24 of the corresponding tooth by means of an ordinary wrench so 105 that the broken tooth can be removed and a new one inserted utilizing the same bolt for its connection and it is obvious that should a tooth bar 17 become broken for any reason it is simply necessary to remove the 110 anchor plates 18 thereof and shift the same lengthwise out of the cylinder.

In their arrangement around the cylinder it will be noted that the teeth 22 are in staggered relation as clearly seen in Figure 1 and it is to be observed that upon certain of the bars it is necessary to fix the outer or end teeth in the plane of the end plates 11. For this purpose certain of the peripheral slots 15 have their side walls cut away to form pockets 27 by means of which the bolts and nuts can be reached and withdrawn in the replacement of these particular teeth.

It is quite obvious from the foregoing that the means shown and described are well adapted to the carrying out of the objects first above mentioned and that the cylinder as proposed by my invention will be strong and durable, is capable of ready repair without requiring particular skill for this purpose, and provides for easy interchange of the parts thereof.

I claim:

1. A thrashing cylinder having circular end plates and an intermediate circular support or partition, said partition and said end plates having longitudinally alined peripheral grooves provided with under cut side walls, tooth bars having flaring inner portions and slideable in the direction of their lengths into and out of the said grooves,

means detachably associated with the tooth bars and engaging the end plates to normally hold the tooth bars against sliding movement, and series of teeth detachably connected to the tooth bars in their length as described.

2. A thrashing cylinder having tooth bars provided with recesses the side walls of which taper vertically and transversely of each bar extending for a portion of the width of the bar, and teeth having portions tapering longitudinally and transversely to interfit the recesses and having shouldered portions to seat against the outer faces of the bars.

3. A tooth bar for thrashing cylinders having a series of recesses in its length, each recess tapering vertically and transversely of the bar, lengthwise and transversely tapering teeth interfitting the said recesses at one end, and a connecting bolt through each tooth and the adjacent portion of the bar for securing the teeth in place, the said recess entering end of each tooth being reduced in one direction to form a shoulder on the tooth abutting the outer face of the bar for the purpose described.

ROBERT H. OWEN.
